CLAIM

The ornamental design for a display screen or portion thereof with icon, as shown and described.

DESCRIPTION

FIG. 1 is a front view of a display screen or portion thereof with icon showing our new design; and,
FIG. 2 is a front view of a second embodiment thereof.
The dot-dash broken line showing of the display screen or portion thereof is for environmental purposes only and forms no part of the claimed design.

1 Claim, 2 Drawing Sheets

See application file for complete search history.

FIG. 1

FIG. 2
